NECKTIE PACKAGING

Walter M. Morse, Troy, N. Y., assignor to Cluett,
Peabody & Co., Inc., Troy, N. Y., a corporation
of New York

Application April 13, 1933, Serial No. 665,892

3 Claims. (Cl. 206—78)

In the distribution of neckties from manufacturers to retailers it is customary to ship in packages of three, six or twelve ties, each tie being folded near the middle with the narrow end under the wide end and the ties being stacked in superposed relationship in a suitable container. When thus folded and stacked the front faces of the wide ends receive impressions, not only of the outlines of the underlying and overlying narrow ends 5 but also of the seams in the rear portions of both ends. After the ties remain in this relationship for an appreciable time the aforesaid impressions form wrinkles which can be removed only by a pressing operation. While these wrinkles are 10 more or less objectionable in practically all neckties they are particularly unsightly in plain-color ties.

The object of this invention is to avoid the aforesaid wrinkles irrespective of the number of 20 ties stacked together and also to avoid the danger of creases due to accidental folds in the ties in the process of packaging. A further object is to attain the aforesaid ends with little if any additional expense over the packaging methods heretofore 25 used.

For the purpose of illustration a typical concrete embodiment of the invention is shown in the accompanying drawing in which:

Fig. 1 is a front elevation of a group of ties in 30 a transparent envelope;

Fig. 2 is an edge view of the group of ties removed from the envelope;

Fig. 3 is a front view of one of the neckties with parts broken away; and

Fig. 4 is a rear view of the wider end of one of the neckties.

The particular embodiment of the invention chosen for the purpose of illustration comprises three tubular neckties 1, 2 and 3, each tie being 40 folded approximately midway between its ends and the three ties being disposed in superposed relationship with the narrow ends 4 and 5 of ties 1 and 2 against each other and the wide ends 6 and 7 of ties 2 and 3 against each other, the 45 wide end 8 of the first tie being presented at the top of the stock and the narrow end 9 of the third tie disposed at the bottom of the stock. Within the wide end of each tie is inserted a strip 10 of cardboard or the like which is tapered to fit the tubular end without substantial stretching. Indeed it is preferable to use relatively thin and soft 50 cardboard which is incapable of stretching the necktie to appreciable extent. For the purpose of preventing the cardboards from accidentally slipping out of the ties in handling or displaying

them, a band 11 of paper or the like may be applied around the portion of each tie containing the cardboard strip, the strip being wedged snugly into the band and the band preferably being applied above the location of the knot when the tie is knotted in use so that any creases or other impressions formed on the tie by the band will not be visible when the tie is in use. For the purpose of holding the ties in the aforesaid superposed relationship I may employ any suitable 60 means, as for example, a paper band 12 and/or an envelope 13, the latter preferably being formed of thin transparent paper. The bands 11 and 12 may also serve to carry suitable indicia such as the name and/or trade-mark of the maker, the 65 type of necktie, the kind of material, etc.

In assembling the illustrated package the bands 11 may be applied to the ties either before or after the cardboard strips are inserted and either by slipping them over the narrow ends of the ties 75 or by wrapping them around the ties and connecting the overlapping ends together. Likewise the band 12 may be applied either by slipping it over the folded ends of the ties or by cementing the ends together after wrapping it around the 80 group.

With the ties folded and stacked as aforesaid the front faces of the wide ends, which are exposed to view when the ties are in use, remain smooth and unwrinkled, irrespective of the pressure with which they are pressed together and irrespective of the length of time they are left packaged. By inserting each cardboard strip slightly beyond the position where its lower edges register with the lower edges of the wide end of the tie, the strips are not visible when the ties are viewed from the front; and by making the strips somewhat smaller than the ties in width, the ties are not substantially stretched or otherwise distorted when the strips are inserted.

With the ties stacked in the usual way, that is front-to-back, the seams at the back of each tie would tend to form impressions in the juxtaposed front of the next tie pressed thereagainst, although the smooth cardboard inserts would greatly reduce this tendency. However, by stacking the neckties alternately front-to-front and back-to-back this tendency is entirely eliminated.

It should be understood that the present disclosure is for the purpose of illustration only and that this invention includes all modifications and equivalents which fall within the scope of the appended claims.

I claim:

1. A package of the character referred to com- 110

prising a plurality of tubular neckties bound in superposed relationship each having a zone whereat the tie is normally knotted in use and a flat strip of sheet material disposed within the 5 larger tubular end of each necktie and extending at least substantially to said zone, said strips being stiff enough and wide enough to avoid wrinkling.

2. A package of the character referred to comprising a plurality of tubular neckties in superposed relationship and a flat strip of sheet material disposed within the larger tubular end of each necktie, each strip having a width approximating the transverse dimension of said end and a length at least approximately equal to the 15 length of that portion of said end which is exposed below the knot when the tie is tied in

normal position, each strip having sufficient body to prevent the superposed edges and seams from forming impressions in the fronts of said ends when the ties are packaged in the aforesaid relationship, and successive neckties being superposed alternately face-to-face and back-to-back. 80

3. A package of the character referred to comprising a plurality of tubular neckties each having a tapered strip of cardboard fitted into its larger end to a point approximately midway between its ends and being folded upon itself approximately at said point, and means for holding the folded neckties in superposed position, successive neckties being superposed alternately face-to-face and back-to-back. 85
